UNITED STATES PATENT OFFICE.

CONRAD DAHL, OF SPRINGFIELD, OHIO, ASSIGNOR OF ONE-HALF TO EARL G. S. TRACY.

AMUSEMENT SWING.

Application filed March 31, 1927. Serial No. 179,791.

REISSUED

This invention relates to a pleasure swing of the rider-propelled type intended especially for use by children, and therefore designed with particular attention to ease and safety of operation. It consists of certain elements and features of construction in combination, as herein shown and described and as indicated by the claims.

In the drawings:
10 Figure 1 is in the nature of a vertical section but shows most of the swing in side elevation, section being taken as indicated at line, 1—1, on Figure 2.

15 Figure 2 is an end elevation of the swing and portions of its supporting frame.

Figure 3 is a top plan view of the swing carriage taken as a section as indicated at the line, 3—3, on Figure 2.

20 Figure 4 is a detail section of the operating lever taken as indicated at line, 4—4, on Figure 1.

Figure 5 is a detail vertical section as indicated at line, 5—5, on Figure 1.

25 Figure 6 is a detail section of the hanger mounting as indicated at line, 6—6, on Figure 2.

As shown in the drawings, the supporting frame for the swing comprises posts, 1, 1, disposed in vertical planes at both sides of 30 the swing carriage and sloping upwardly and convergently for connection with head castings, 2—2, which in turn are transversely joined by a large tubular cross bar, 3, and a smaller cross bar, 4, as indicated in Figures 35 1 and 2. At each side of the frame the head casting, 2, is made in two parts separable at the vertical median plane which is common to the cross bars, 3 and 4, and the two parts are clamped together by bolts, 5, to embrace 40 said cross members, 3 and 4. Oblique braces, 6, extend downwardly and outwardly from the head castings, 2, being connected thereto by terminal sockets, 7, formed with clamping collars, 8, which engage the laterally projecting ends of the cross bar, 3. The supporting frame thus consists of two sets of three-legged structures spaced apart by the parallel vertical planes of the uprights, 1, and tied together by the cross bars, 3 and 4, at 45 their upper ends. The lower ends of the post members may be anchored in any convenient manner; they are shown with foot sockets, 9, which may be secured to a wooden or concrete floor or otherwise firmly fastened in 50 the ground according to circumstances of location. The cross bars, 3 and 4, may be of

any desired length, as indicated by the broken representation of these parts in Figure 2; in some cases a single set of uprights may support two or three swing carriages. To stiffen the construction and also to support the swing carriage I provide hanger brackets between the bars, 3 and 4 in the form of split clamps, 10, of triangular form secured by clamping bolts, 10⁶, in 60 spaced relation on the cross bars, 3 and 4.

The swing carriage comprises a seat plank, 11, to the underside of which are attached brackets, 12, supporting foot boards, 13, at each side of the plank, 11, and tied together laterally by cross bars, 14; sloping braces, 12⁷⁰, may also be provided at the middle of the carriage. Sloping foot rests, 15, are slidably secured to the foot boards, 14, by means of guide straps, 16, and each of them is adjustable longitudinally by the insertion of a pin, 17, on the under side of the foot rest in one of a series of holes, 18, in the foot board, 13.

To the upper side of the seat plank, 11, a 80 rigid frame is secured consisting of uprights, 20, spaced apart laterally in pairs, each pair being connected to each other in any suitable manner as by integral diagonal portions, 21, and horizontal bars, 22; the upper ends of the uprights, 20, are formed with bosses, 25, to carry pivot bolts, 26, by which the rigid carriage structure is attached to hanger bars, 27, dependent from triangular yokes, 28, attached to their upper ends. The uprights 85 90 are laterally joined by tie bolts, 23, with spacing sleeves, 24, interposed.

The yokes, 28, are journaled on bearing rods, 29, carried by the triangular hanger brackets, 10, and preferably anti-friction 95 rollers, 30, are used at this connection as indicated in Figure 6.

The swing carriage is thus swung from the bearing rods, 29, by parallel hanger bars, 27, of exactly equal length with the result that 100 as the swing travels through its range of movement the seat plank, 11, remains horizontal at all positions, as indicated in dotted lines in Figure 1, and the angular movement of the hangers, 27, about the pivots, 26, takes 105 place at a point far enough above the seat plank, 11, to avoid any danger of striking the heads of the riders.

For operation of the swing the hanger bars, 27, are extended downwardly below the 110 pivots, 26 at 31 and these depending portions are pivotally connected to a horizontal

operating member, 32, with handles, 33, mounted at its ends. The member, 32, remains parallel to the seat plank, 11, throughout the movement of the swing, but moves 5 longitudinally with respect to the seat so that as the riders exert pressure or pull horizontally upon the handles, 33, they tend to move the hangers, 27, away from strictly vertical positions, and thus produce the 10 swinging motion of the carriage. The member, 32, consists of two similar halves separable at a vertical plane and connected by tie bolts, 34. Pivot sleeves, 35, are secured between the halves of the part, 32, by screws, 15 36, and bushings, 37, carried by the extensions, 31, of the hanger bars, 27, provide the pivotal bearings between these parts. To permit of varying the leverage or mechanical advantage of the operating member, 32, 20 I prefer to arrange several bushings, 37, in the lower ends, 31, of the hangers, 27, so that the pivot sleeves, 35, may be shifted from one set of bushings to another when desired. As shown in Figure 5 the pivots, 25 35, are engaged in the lowest of the three bushings, 37; for connection with the upper bushings the member, 32, may be turned upside-down to provide proper clearance of the parts for operation. Thus for smaller children the member, 32, is connected in the 30 lowest bushings, 37, thus bringing the handles, 33, conveniently near the seat plank, 11, and providing the greatest mechanical advantage in operation, while for larger 35 children the handles, 33, may be raised to a position farther from the seat and by connection with one of the upper sets of bushings, 37, will provide a shorter leverage by which the larger and stronger children can 40 operate the swing with a somewhat shorter working stroke.

The sides of the operating member, 32, are fitted between the uprights, 20, of the carriage frame with only slight clearance so 45 that there is little chance that the riders will catch their fingers between these parts, particularly since there is no occasion for placing the hands on the portion of the member, 32, which travels back and forth between 50 the uprights, 20. The travel of the member, moreover, is always in a direction perpendicular to the edges of the uprights, 20, so that there is no wedging or pinching action 55 possible between these parts.

Owing to the connection of the member, 32, to the lower ends, 31, of the hangers, 27, the motion of the operating part, 32, is in the same direction as that of the swing carriage so that the inertia of any body movement 60 by which the riders accompany their pushing or pulling efforts on the handles, 33, is added to such efforts and renders the operation of the swing easier and more natural than if the body motion were opposite to the direction of swing movement. 65

A safety feature to prevent injury to bystanders who might come too close to the path of the swing carriage is provided in the form of rubber armoured buffer wheels or disks, 38, attached to the under side of the 70 seat plank at each end, preferably on pivots, 39, which are not rigidly secured to the seat plank but are attached thereto by coiled spring mounting members, 40, so that the buffer wheels, 38, will yield bodily upon 75 colliding with a person in the path of the swing and thus avoiding serious injury.

I claim:—

1. In a pleasure swing, the combination of 80 a supporting frame, pivoted hangers depending therefrom in parallel relation, a swing carriage including a seat and a portion extending rigidly upward therefrom having pivotal connection with the hangers, said hangers extending below such pivotal 85 connections, and a horizontally movable operating member connecting the downwardly extended portions of the hangers.

2. In a pleasure swing, the combination of 90 a supporting frame, pivoted hangers depending therefrom in parallel relation, a swing carriage including a seat and a portion extending rigidly upward therefrom having pivotal connection with the hangers, said hangers extending below said pivotal 95 connections, a horizontally movable operating member disposed above the plane of the seat and vertically adjustable connections between said operating member and the downwardly extending parts of said hangers. 100

3. In a pleasure swing the combination of 105 a supporting frame, pivoted hangers depending therefrom in parallel relation, a swing carriage including a seat and a portion extending rigidly upward therefrom 110 having pivotal connection with the hangers, a horizontally movable operating member disposed above the plane of the seat, and connections between said member and the 115 hangers whereby the movement of the operating member over the seat is in the same direction as the bodily movement of the swing carriage with respect to its supporting frame.

4. In a pleasure swing the combination of 115 a supporting frame, pivoted hangers depending therefrom in parallel relation, a swing carriage including a seat plank with foot boards depending therefrom at the sides, longitudinally adjustable foot rest 120 members on said foot boards, a portion extending rigidly upward from the seat plank and having pivotal connection with the hangers at a distance above the plane of the seat at the middle of its length, a horizontally 125 movable operating member disposed between the plane of the seat and said pivotal connections, said hangers having portions which extend rigidly downward below said pivotal connections for engagement 130

with said operating member and handles arranged at opposite ends of said member.

5. In a pleasure swing, a supporting frame comprising two upright sections spaced 5 apart laterally and connected at their upper ends by a pair of bars disposed one above the other; a pair of brackets engaging said connecting bars and spaced apart thereon within the space between the upright sections, a pair of parallel bearing rods horizontally supported by said brackets spaced apart in the direction of movement of the swing, and a swing carriage with hangers 10 extending upwardly therefrom pivotally supported by said bearing rods.

6. In a pleasure swing, the combination of a supporting frame, pivoted hangers depending therefrom in parallel relation, a swing carriage including a seat and a frame 20 portion extending rigidly upward therefrom comprising laterally spaced uprights and having pivotal connection with the hangers

at a distance above the plane of the seat, a horizontally movable operating member disposed between the uprights of said carriage 25 frame and between the plane of the seat, and said pivotal connection with the hangers, said hangers having portions which extend rigidly downward for engagement with said operating member, and said member projecting longitudinally from the carriage frame with a handle secured to its projecting portion having a range of operating movement entirely outside said frame.

7. In a pleasure swing, the combination of 30 a supporting frame, a carriage and pivoted hangers depending from the frame in parallel relation for connection with the carriage, together with a buffer wheel associated with the carriage on a substantially vertical 35 pivot, said wheel being peripherally padded and its pivot being yieldingly connected to the carriage.

CONRAD DAHL.
